UNITED STATES PATENT OFFICE.

JOSEF H. VON REHDER, OF WINFIELD, NEW YORK.

CORNER-BEAD FOR BUILDING CONSTRUCTIONS.

1,035,278.

Specification of Letters Patent. Patented Aug. 13, 1912.

Application filed April 13, 1912. Serial No. 690,503.

To all whom it may concern:

Be it known that I, JOSEF H. VON REHDER, a citizen of the United States, residing at Winfield, county of Queens, and State of New York, have invented a new and Improved Corner-Bead for Building Constructions, of which the following is a specification:

This invention relates to a corner bead of novel construction adapted to effectively protect interior corners of fire-proof, and other buildings.

In the accompanying drawing: Figure 1 is a horizontal section through a wall provided with a corner bead embodying my invention; Fig. 2 a perspective view of the corner bead with the clip omitted; Fig 3 a horizontal section of the corner bead and interlocking clip, and Fig. 4 a perspective view of a section of the corner bead and clip.

The corner bead consists essentially of a continuous strip of sheet metal bent to form at its center a tube or "bull's nose" 10. From the seam of this tube, the two sections of the bead extend radially outward and in close contact with each other to form a doubled solid or imperforate neck 11. From the inner ends of this neck, the two sections of the bead are laterally deflected to form a pair of wings 12 which project at right angles from each other. These wings 12 are provided with nail holes 13 and with a series of alined plaster apertures 14, the latter being shown to be of triangular form. In applying the bead, constructed as described, the wings 12 are made to straddle the corner 15 of the wall to be protected to which they are secured by nails 16 driven through holes 13. The plaster coating 17 is now applied so as to completely cover up neck 11 and also bead 10, such coating by entering apertures 14 being securely bound to the bead.

With fire proof constructions, it may happen that the nail holes 13 do not register with the seams of the walls. In order to effect an accurate alinement between such seams and the nail holes, I provide a number of clips 18, each composed of a bendable sheet metal strip. This strip is adapted to be passed through a pair of horizontally alined apertures 14 of the bead, during which passage, it is bent centrally at right angles to form two arms that extend in parallelism with wings 12 and project a suitable distance beyond the same. Each of these arms is provided with a downwardly opening notch or vertical slit 19 adapted to engage over the edge of wing 12 at the lower perimeter of that aperture 14 through which said arm is passed, so that in this way the clip is securely interlocked with the bead. Within the protruding ends of clips 18 are formed one or more nail holes 20, which have been so punched as to accurately correspond to the seams of the wall. In this way beads of any size may be securely nailed to the wall without requiring a previous accurate fitting. The number of clips required for each bead depends upon the length of the latter and may be varied to suit the judgment of the builder.

I claim:

A corner bead comprising a central tubular section, a doubled neck extending radially therefrom, and a pair of wings extending from the neck and having alined apertures combined with nailing clips extending through some of said apertures and having vertical downwardly opening slits that straddle the edges of the wings at the lower perimeters of the apertures.

JOSEF H. VON REHDER.
